Inventor

Frederic Hewitt

United States Patent Office.

FREDERIC HEWITT, OF BLOOMFIELD, NEW JERSEY.

Letters Patent No. 97,774, dated December 14, 1869.

IMPROVEMENT IN FLUTING-MACHINES.

The Schedule referred to in these Letters Patent and making part of the same

To all whom it may concern:

Be it known that I, FREDERIC HEWITT, of Bloomfield, in the county of Essex, and State of New Jersey, have invented a new and useful Improvement in Fluting-Machines; and I do hereby declare that the following is a full, clear, and exact description of the same, reference being had to the annexed drawings, making a part of this specification, in which—

Figure 1 is a longitudinal elevation of my invention, and

Figure 2, an end elevation of the same.

The same letters indicate like parts in both figures.

The nature of my invention consists in dispensing with the rollers heretofore used in fluting-machines, and using, instead, two flat or curved surfaces or dies, having the necessary and corresponding corrugations, flutes, crimps, or other patterns formed on their surfaces; these dies, forming the faces of two boxes or heater-receptacles, one upper and one lower, and which may be pressed together in any convenient manner; said dies being heated by heaters inserted into the before-mentioned boxes or receptacles, so that the material to be fluted, being placed between said dies, and pressure being applied, may receive an impression corresponding to the patterns on the dies.

My invention further consists in an apparatus convenient for transmitting pressure to the dies and heater boxes, and so arranged that the parts thereof are out of the way of the work to be operated upon.

To enable others to understand the nature and construction of my invention, I will proceed to describe it with reference to the drawings, in which—

A, A' are the two heater-boxes, the faces of which, B, B', are formed with the flutes or other patterns intended to be impressed on the material operated upon.

These faces may either be separate pieces from the

heater-boxes, to which they may be fastened, in any convenient manner, or they may be made in one piece with them.

If F are the heaters, placed in their receptacles, to heat the dies B, B'.

One of these boxes, in this case the lower, is made fast to the standard M and clamp J, the standard forming a fulcrum, at E, for the lever C, at one end of which, at E', are attached the other heater-box and die.

At a point, N, intermediate between E and E', is a link, D, connecting the lever C with the lever G, which has its fulcrum at I, so that pressure applied at the end, K, of lever G, is transmitted, by link D, to lever C, and so to the heater-box A and die B.

The lever C is continued to L, where is attached a spring, H, which raises the end E', and heater-box and die, when the pressure on the lever G is relieved.

A weight may be substituted for the spring, if desired.

The hole K, in lever G, is for the purpose of attaching a cord or stirrup, by which the pressure may be applied by the foot, leaving the hands at liberty to manipulate the material operated upon.

The clamp J is for the purpose of attaching the machine to the table or work-bench.

What I claim as new, and desire to secure by Letters Patent of the United States, is—

The combination and arrangement of the heater-boxes A, B, A', B', lever C, link D, spring H, and lever G, operated as shown and described.

FREDERIC HEWITT.
